UNITED STATES PATENT OFFICE

96,906

DESIGN FOR A WATER CYCLE

Levitt Luzern Custer, Oakwood, Ohio

Application July 13, 1935, Serial No. 57,617

Term of patent 3½ years

To all whom it may concern:

Be it known that I, Levitt Luzern Custer, a citizen of the United States, residing in the city of Oakwood, in the county of Montgomery and State of Ohio, have invented a new, original, and ornamental Design for a Water Cycle, of which the following is a specification, reference being had to the accompanying drawing, forming part hereof.

The figure is a perspective view of a water cycle, showing my new design.

I claim:

The ornamental design for a water cycle, as shown.

LEVITT LUZERN CUSTER.
